CLAIM

The ornamental design for an anchor for a floor, as shown and described.

DESCRIPTION

FIG. 1 is a perspective of an anchor for a floor according to the present disclosure;

FIG. 2 is a front view thereof;

FIG. 3 is a right side view thereof;

FIG. 4 is a top plan view thereof;

FIG. 5 is a rear view thereof;

FIG. 6 is a left side view thereof; and,

FIG. 7 is a bottom plan view thereof.

The broken lines in the drawings depict portions of the anchor for a floor that form no part of the claimed design.

1 Claim, 7 Drawing Sheets
